UNITED STATES PATENT OFFICE.

RENÉ BARON, OF PARIS, FRANCE.

PENDANT FOR LIGHTING APPARATUS AND THE LIKE.

Application filed July 18, 1923. Serial No. 652,424.

To all whom it may concern:

Be it known that I, RENÉ BARON, a citizen of the Republic of France, and resident of Paris, France, have invented certain new and useful Improvements in Pendants for Lighting Apparatus and the like, of which the following is a specification.

The present invention has for its object to provide an improved winding-up pendant whereby a lighting apparatus such as an electric lamp or the like can be raised, lowered or maintained in equilibrium at any given height with respect to a ceiling or the like, and whereby also the weight of the said apparatus can be varied within relatively wide limits without destroying the stable equilibrium of the pendant and, moreover, without necessitating any adjustment for each such variation in the weight of the suspended apparatus.

According to the invention, the improved winding-up pendant having a stable equilibrium is constituted by a C-shaped yoke formed at each of its extremities with an eyelet through which the suspension cable passes. This yoke supports at substantially the middle of its length a spindle on which a spool, around which is wound-up the suspension cable, is free to rotate; in a cavity formed in the said spool is located a barrel containing a spiral spring hooked up by one of its ends on the said spindle and by its opposite end on the peripheral wall of the barrel, the latter being keyed on to the spool. This barrel is provided externally with a tube enclosing a portion of the length of the said spindle; on this tube are wound up three or four coils of a wire secured by one of its ends on the C-shaped yoke, the said coils constituting a braking element adapted for stopping, within predetermined limits, the rotation of the spool in the direction corresponding to the unwinding of the cable.

In the event of the suspension cable being a flexible pipe for conveying a combustible fluid or an electric conductor for carrying an electric current to the lighting apparatus, it is preferable to use a twofold winding thus obviating the necessity of interposing a transmission device between the main and the said lighting apparatus in which case the suspension cable directly connects the main to the said apparatus without any break of continuity.

In order to obtain a twofold winding,

the cable is hooked up midway of its length on the spool and the rotation of the said spool under the action of the spiral spring then performs the winding-up of the two parts of the cable in opposite directions.

For the purpose of preventing the two parts of the cable from overlapping each other when they are wound-up on the spool, the spindle of such spool is fixed to the C-shaped yoke obliquely with respect to the vertical passing through the axis of suspension. By this arrangement, the said two parts of the cable are wound-up on either sides of the hook fixed midway of the width of the spool.

In order that this invention may be more clearly understood and readily carried into effect, it will now be described with reference to the accompanying drawing, wherein—

Figure 1 is an elevation partly in section of a winding-up pendant embodying the invention and comprising a double-action spool adapted for rotating around a spindle supported obliquely by means of a C-shaped yoke located in a casing constituted by two juxtaposed shells shown in section and engaging each other by their peripheral edges.

Figure 2 is a diametrical sectional view of the barrel, assuming same to be released from the hollowed portion of the spool, the bottom part of such barrel being provided externally with a tube for enclosing the spindle on which is attached the spiral spring.

Figure 3 is a sectional view on the line *x—x* of Fig. 2.

Figure 4 is a side elevational view of a further winding-up pendant embodying a modification of the invention and comprising a spool on which the cable is wound up in one direction only, the extremities of the spindle passing through the said spool being supported by a casing comprising two shells shown in section as surrounding the device.

According to any of these two embodiments, (Figure 1 or 4) the improved pendant is constituted by a hollow spool 1 in a portion of the hollowed part or cavity of which is located a barrel casing 7 in which is contained a spiral spring 8, the periphery of the said casing having a rib 7^a (see Figure 2) adapted for sliding in a correspondingly shaped groove 1^a formed

in the spool 1 and for thus firmly connecting the casing 7 and the said spool 1. One extremity of the spring 8 is formed with an elongated hole through which passes a pin 9 fixed to the spindle 2 around which the spool rotates, the other extremity of the spring 8 being folded for abutting against a hook 9^a formed on the inner peripheral wall of the casing 7. By this arrangement, the spool 1 is connected to the spindle 2 and may rotate around the latter. The bottom of the barrel casing 7 is provided laterally and externally with a tube 11 for enclosing a part of the length of the spindle 2. Around such tube 11 are wound up the coils 10 of a spring wire fixed by one of its ends at 12 to the yoke 3 (see Figure 1) or alternately to one of the shells 140 (see Figure 4).

In the embodiment represented in Figure 1, the spindle 2 is supported on one side only by a C-shaped yoke 3 and positioned obliquely, as clearly shown, substantially midway of the internal height of the two juxtaposed metallic shells 4 engaging each other by their peripheral edges at 5. The yoke 3 is fixed to the shells 4 by screwing up rings 6 on the corresponding threaded portion of insulating sleeves *d* positioned at the extremities of such yoke, said sleeves *d* being secured on the latter by screws *e*. On the rim of the spool 1 and substantially midway of its length is fixed a hook *c* around which it is possible to pass the suspension cable *a* *b* which is thus fastened to the spool and allows of the winding up of the two parts *a* and *b* of said cable according to two opposite directions.

The spiral spring 8 is sufficiently strong when taut to raise the pendant itself (that is to say when no weight is suspended from the said pendant). Therefore, when one raises, for instance by hand, the apparatus (representing the said weight) suspended by the part *b* of the cable, the weight of such apparatus no more exerting itself on the pendant, the said spring 8 raises it and winds up the cable on the spool 1. When afterwards one ceases to push the apparatus up it is obvious that, if braking means were not provided, its weight would overcome the tensional resistance of the said spring 8 and cause the said apparatus to descend. However this does not occur because such tendency to downward motion is checked and the stability of the suspended apparatus automatically obtained due to the braking action exercised by the coils 10 of the wire fixed at one end 12 and wound up around the tube 11 connected to the barrel, the other end 13 of said wire being free relatively to the tube 11. Owing to this construction, when the upward motion of the apparatus is interrupted, its own weight tends to unwind the

spool but this tendency is overcome and the unwinding motion prevented since the tube 11 then rotates around the spindle 2 simultaneously with the barrel and, by reason of its friction, carries with it the free end 13 of the braking wire, this gradually ensuring the jamming of the other coils 10 of the said wire and thus stopping the rotation of the spool 1 in the unwinding direction and at the same time the downward motion of the apparatus which has been left to the action of gravity.

The braking action is adjusted by varying the number of the coils of the wire 10 and their initial friction against the tube 11 so that such braking action may support a maximum weight beyond which it becomes insufficient to prevent the unwinding.

In view of the foregoing, it is apparent that, to cause the downward motion of the lighting apparatus or the like, all that is necessary is to pull thereon so that the stress thus exerted adding itself to the weight thereof exceeds the predetermined maximum. As soon as such pulling stress is interrupted, the reaction of the brake is sufficient to stop the unwinding.

In the embodiment represented in Figure 4, the spindle 20 is carried by the casing 140. The casing is pierced at its top portion with a hole *d'* through which the suspension cable *a'* passes; this cable is attached at *c'* to the spool 1. On the bottom part of the casing is fixed a hook 15 from which the lighting apparatus or the like which is to be raised or lowered is suspended.

What I claim and desire to secure by Letters Patent is;

1. An automatically balanced winding-up pendant for raising, lowering or maintaining at any desired height, a lighting apparatus or the like, comprising a hollow spool on which is wound up the suspension cable leading to said apparatus, a barrel casing containing a spiral spring, said casing being located firmly within said spool, said spring being hooked up to the spindle passing through said spool, a tube connected to the bottom of the barrel casing and extending outwardly therefrom along its axis of rotation, and a brake constituted by adjacent turns of helix formed by a wire twisted around said tube, one end of said wire being attached to a stationary point, the said turns of helix jamming the said tube and thus performing the braking action and stopping the downward motion of the apparatus when the latter is left to the action of gravity.

2. An automatically balanced pendant according to claim 1, in which the spindle passing through the spool is carried by a C-shaped yoke formed at each of its extremities with a hole for receiving insulat-

ing sleeves, said spindle being supported obliquely at substantially the middle of the height of said yoke to make it possible for the suspension cable passing through said 5 sleeves and attached substantially midway of its length the spool to be wound up by part on the said spool according to two op-

posite directions on either sides of the said hook for ensuring a double-action winding-up.

10

In testimony whereof I have signed my name to this specification.

RENÉ BARON.
